UNITED STATES PATENT OFFICE

2,416,225

PIANO AMPLIFIER

John H. Scott, Tulsa, Okla.

Application September 14, 1944, Serial No. 554,066

3 Claims. (Cl. 84—189)

1

This invention relates to sound amplifying devices and more particularly to a sound amplifying device for a percussion instrument.

An object of this invention is to provide a sound amplifying means for a percussion instrument, such as a piano or like instrument, which is attached to the soundboard and will amplify the vibrations of the soundboard.

Another object of this invention is to provide in combination with the soundboard of a percussion instrument a sound amplifying attachment which is adapted to be secured to the soundboard at spaced points about the latter.

A further object of this invention is to provide a sound amplifying cone for attachment to a percussion instrument soundboard, the cone including a vibration transmitting means whereby the vibrations of the soundboard will be communicated to the cone outwardly of the apex thereof.

To the foregoing objects, and others which may hereinafter more fully appear, the invention consists of the novel construction, combination and arrangements of parts, as will be more specifically referred to and illustrated in the accompanying drawings, but it is to be understood that changes, variations, and modifications may be resorted to which fall within the scope of the invention as claimed.

In the drawings:

Figure 1 is a detail rear elevation, partly broken away, of a sound amplifying means constructed according to an embodiment of this invention.

Figure 2 is a sectional view taken on the line 2—2 of Figure 1.

Referring to the drawing, the numeral 10 designates generally a soundboard which forms a part of a percussion instrument, and is provided with an outstanding bracing rib 11. In order to provide a means whereby the audible vibrations of the soundboard 10 may be amplified, I have provided an amplifier construction generally designated as 12, which is secured to the rib 11 or to any convenient location on sound board 10 and extends outwardly therefrom. The amplifier construction 12 includes a fibrous cone 14 which has extending from the apex thereof a sleeve 13. A sound post or supporting member 15 is glued or otherwise firmly secured as at 16 to the outer side of the rib 11 and is of such length as to extend interiorly of the cone. The sound post 15 is secured to the sleeve 13 by glue or other suitable fastening means so that the apex or small end of the cone 14 will be firmly supported from the post 15.

2

A disc shaped vibration transmitting member 17 is secured to the outer end of the post 15, and preferably a headed screw 18 extends through the disc 17 and through the center of the post 15 and engages the rib 11. The disc 17 is formed with convex inner and outer surfaces 19 and 20 and the outer marginal portion of the disc 17 is of reduced thickness and is secured as by glue 21 or other fastening means to the inner side of the cone 14 outwardly of the apex thereof.

A fibrous disc 22 is glued or otherwise firmly secured to the outer convex side 20 of disc 17 and is formed at its outer marginal portion with a flared skirt 23 tapered coincident with the taper 15 of the cone 14 and secured as by glue or other fastening means 24 to the inner side of the cone 14.

In the use of this amplifying means the post 15 is glued and secured by the screw 18 or by hard wood dowel to the outer side of the rib 11 or to any convenient location of the surface of soundboard. There may be as many of these cones secured to the soundboard as may be desired and they may be spaced about the soundboard at appropriate points for amplifying the audible and inaudible vibrations of the soundboard. As soundboard 10 vibrates and rib 11 also vibrates these vibrations will be communicated to sound post 15 and from sound post 15 the vibrations will be picked up by disc 17 and as this disc is firmly secured at its outer margin to cone 14, the latter will vibrate, and these vibrations will be amplified and will be directed rearwardly of the soundboard 10.

What I claim is:

1. As a new article of manufacture, a sound amplifying means for attachment to a sound vibrated member comprising a cone-shaped body, a supporting member fixed to and extending from the apex of said body, said supporting member extending inwardly of said body from said apex, a vibratory disc fixed to the inner end of said supporting member and to said body spaced from the apex of the latter, and a fibrous disc-shaped member secured to said disc and said body.

2. A sound amplifying attachment for a soundboard comprising a cone-shaped body, a cylindrical sleeve extending from the apex of said body, a sound post fixed within said sleeve and extending inwardly of the apex of said body, a disc fixed to the inner end of said sound post, and means securing the marginal edge of said disc to the inner side of said body spaced from the apex of the latter, said disc having convex opposite sides.

3. A sound amplifying attachment as set forth in claim 2 including a fibrous disc-shaped member secured to said disc, said disc-shaped member including a flared marginal portion fixed to the inner side of said body, and means extending through and secured to said disc-shaped member, said disc and said sound post for fixing said attachment to the sound board.
